CLAIM

The ornamental design for a radioactive therapeutic device, as shown and described.

DESCRIPTION

FIG. 1 is a perspective view of a radioactive therapeutic device;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of the radioactive therapeutic device in a closed position;

FIG. 9 is a left side elevational view in the closed position thereof;

FIG. 10 is a right side elevational view in the closed position thereof;

FIG. 11 is a front elevational view in the closed position thereof;

FIG. 12 is a rear elevational view in the closed position thereof;

FIG. 13 is a top plan view in the closed position thereof; and,

FIG. 14 is a bottom plan view in the closed position thereof. The broken lines shown in the drawing views are included for the purpose of showing environmental structure that forms no part of the claimed design.
